Primary Examiner — Marie D. Fast Horse

(57) **CLAIM**

The ornamental design for a docking station, as shown and described.

DESCRIPTION

FIG. 1 is a perspective view of first embodiment of a docking station showing my new design;

FIG. 2 is another perspective view of use state thereof;
FIG. 3 is a front view thereof;
FIG. 4 is a back view thereof;
FIG. 5 is a left side view thereof;
FIG. 6 is a right side view thereof;
FIG. 7 is a top plan view thereof;
FIG. 8 is a bottom plan view thereof;
FIG. 9 is a perspective view of second embodiment of a docking station showing my new design;
FIG. 10 is another perspective view of use state thereof;
FIG. 11 is a front view thereof;
FIG. 12 is a back view thereof;
FIG. 13 is a left side view thereof;
FIG. 14 is a right side view thereof;
FIG. 15 is a top plan view thereof;
FIG. 16 is a bottom plan view thereof;
FIG. 17 is a perspective view of third embodiment of a docking station showing my new design;
FIG. 18 is another perspective view of use state thereof;
FIG. 19 is a front view thereof;
FIG. 20 is a back view thereof;
FIG. 21 is a left side view thereof;
FIG. 22 is a right side view thereof;
FIG. 23 is a top plan view thereof;
FIG. 24 is a bottom plan view thereof;
FIG. 25 is a perspective view of fourth embodiment of a docking station showing my new design;
FIG. 26 is another perspective view of use state thereof;
FIG. 27 is a front view thereof;
FIG. 28 is a back view thereof;
FIG. 29 is a left side view thereof;
FIG. 30 is a right side view thereof;
FIG. 31 is a top plan view thereof;
FIG. 32 is a bottom plan view thereof;
FIG. 33 is an enlarged view of portion of FIG. 2;
FIG. 34 is an enlarged view of portion of FIG. 10;
FIG. 35 is an enlarged view of portion of FIG. 26; and,
FIG. 36 is an enlarged view of portion of FIG. 18.
The broken lines in the drawings depict portions of the docking station that form no part of the claimed design.
